HAND-HELD MOTOR-DRIVEN SHEAR

Filed April 28, 1951

UNITED STATES PATENT OFFICE

2,631,370

HAND-HELD MOTOR-DRIVEN SHEAR

Charles B. Gray, Springfield, Pa.

Application April 28, 1951, Serial No. 223,599

5 Claims. (Cl. 30—241)

1

This invention relates generally to motor-driven sheet-metal cutting tools and more particularly to improvements in the construction of hand-held, electrically operated shears of the type shown and described in my prior United States Letters Patent No. 1,922,846 of August 15, 1933, to which reference is made for an understanding of the general features of the tool and of the operation of all parts thereof not specifically described herein.

Among the objects of the present invention is to provide a motor-driven shear which is exceedingly rugged, yet simple in design and construction and which is efficiently operative to quickly and accurately cut sheet metal stock along straight lines as well as along curved lines of very small radii or of irregular configuration.

An important object of the invention is to provide the shear with a novel construction of demountable anvil which is adapted to be readily secured to and removed from the operating head of the tool and which serves not only as the support for the lower fixed cutting blade of the shear but also as the guide for the upper vertically reciprocable cutting blade which contacts with the fixed blade to shear the stock fed through the tool.

Still another and important general object of the invention is to provide the shear with a work-supporting and guiding plate, otherwise known as an anvil, of such design and construction as to facilitate cutting the stock along curves of exceedingly small radii regardless of whether the curved lines of cut extend clockwise away from the vertical axis of the coacting cutting blades or counter-clockwise about said axis.

A further object of the present invention is to provide an anvil which is of such design and construction and which is so fitted with a lower stationary cutting blade as to facilitate insertion of said blade into and through a small opening formed in the stock for the making of inside cuts in the stock, as where it is desired to cut out parts of pre-formed sheet metal members without cutting through a marginal edge of the same.

A still further object of the invention is to provide an improved disposition of the lower stationary cutting blade in the anvil to more securely lock it in place and so prevent unintentional or accidental displacement thereof relatively to its coacting reciprocating blade; to lessen the strain to which the unsupported end of the anvil is subjected during operation of the

2

tool; to facilitate adjustment of the lower cutting blade as it becomes worn in use; and to generally strengthen and reinforce the unsupported end of the anvil upon which the stationary cutting blade is mounted.

Other objects and advantages of the present invention will appear more fully hereinafter, it being understood that the present invention consists in the combination, construction, location and relative arrangement of parts, all as will be more fully described hereinafter, as is shown in the accompanying drawings and will be pointed out in the appended claims.

In the said accompanying drawings:

15 Figure 1 is a side elevational view of a shear constructed in accordance with and embodying the principles of the invention;

20 Figure 2 is a front elevational view of the shear with the operating head thereof shown partly in section;

Figure 3 is a transverse sectional view as taken along the line 3—3 of Figure 1;

Figure 4 is a transverse sectional view as taken along the line 4—4 of Figure 1;

25 Figure 5 is a vertical sectional view as taken along the line 5—5 of Figure 2;

Figure 6 is a bottom plan view of the operating head of the tool as viewed from the line 6—6 of Figure 1; and

Figure 7 is an elevational view showing the demountable anvil separated from the operating head of the tool.

Referring now more particularly to the drawings, it will be observed that the shear of the present invention is of a form and construction adapted to be held conveniently in the hand of the operator, the operating head of the tool, designated generally by the reference numeral 10, being secured in any suitable manner to the forward end of the casing 11 in which is housed an electric motor 12 for driving a main shaft 13 through the intervention of a gear train designated generally by the numeral 14. The main drive shaft 13 is provided at its end with an eccentric 15 which operates upon an eccentric crank 16 to effect vertical reciprocation of a cutter bar 17 which is generally of circular cross section and extends downwardly through a tubular guide and bearing sleeve 18 provided at the forward end of the casing 11. The construction of the casing 11 and the design and disposition of the motor 12 and the gear train 14 therein may be varied as desired, it being merely noted in this connection that the casing 11 is preferably provided with a hand-hold 19 which is fitted with

50

45

55

a finger-actuated electric switch 20 for controlling the operation of the motor. The tubular guide and bearing sleeve 18 may be formed as an integral depending extension of the gear box portion 21 of the casing 11 or it may be secured thereto as a separate removable part.

As most clearly appears in Figures 4, 5, and 6, the lower end of the cutter bar 17 is notched out at one side thereof, as at 22, to provide a vertically extending channeled seat for a cutting blade 23 having a beveled shearing edge 24 which projects below the open end of the channeled seat 22. This cutting blade 23 is provided in its outer surface with a vertically elongated recess the bottom of which is slotted, as at 25, in registry with a tapped hole 26 formed in the cutter bar 17. A screw 27 disposed with its enlarged head in the recess of the cutting blade and with its shank projecting through the slot 25 and into the tapped hole 26 serves to secure the cutting blade 23 in vertically adjusted position within its channeled seat 22. In order to further secure the cutting blade 23 in position against longitudinal shifting under the impact of each shearing stroke, the upper end of the blade is backed up by a headed screw 28 the shank of which is threaded into the cutter bar 17 in vertical alignment with the blade 23. It will be apparent by that simple rotation of the screw 28 in one direction or the other, its head 29 may be shifted lengthwise of the channeled seat 22 to provide a suitably located upper abutment for the cutting blade 23, the screw 27 being then employed to securely lock the blade in its seat with the upper end of the blade in abutment with the head of the backing screw 28. In order to facilitate adjustment of the latter, its head 29 is provided with circumferentially spaced holes 30 for reception of a suitable pin (not shown) employed to rotate the screw as desired.

Adapted for detachable securement to the lower end of the depending tubular guide and bearing sleeve 18 is a combination unit 31 which serves not only as an anvil, or bed-plate for supporting and guiding the work through the shearing head of the tool, but also as a guide for insuring rectilinear reciprocation of the cutter bar 17 with its associated cutting blade 23 and as a support for the lower stationary cutting blade 32 with which the reciprocating blade 23 coacts in the shearing operation.

It will be noted that the combination unit 31 is provided with a central portion in the form of an anvil 31^a of generally arcuate shape in top plan, the upper flat surface of this anvil spiralling downward from one end toward the other thereof and the thickness of the anvil 31^a being reduced from its outer peripheral edge 33 inwardly toward its inner edge 34. The latter edge follows a curvature of extremely small radius to provide an opening 35 which laterally communicates with an open-ended notch 36 extending lengthwise of the shearing head in the immediate region of the reciprocating cutting blade 23.

Extending upwardly from the elevated end of the spiral anvil 31^a is a tubular post 37 which is provided at its upper end with a radially extending flange 38 adapted to be bolted to a complementally formed flange 39 provided at the lower end of the depending guide and bearing sleeve 18. The tubular post 37 is of the same diameter as that of the sleeve 18 and constitutes a downward extension of the latter when the registering flanges 38 and 39 are bolted as by

the bolts 39^a. It will be noted that the tubular post 37 is vertically notched along one side thereof, as at 40, to provide a vertically extending guideway for the reciprocating cutting blade 23, the opposite side edges of which latter respectively engage the corresponding side edges of the guide notch 40 to prevent twisting of the cutting blade angularly with respect to its vertical axis of reciprocation. Thus, the post 37 of the anvil member unit 31 serves not only to mount the latter operatively in position with respect to the reciprocating shearing blade 23, but also to guide the latter for reciprocation along a definite rectilinear line of travel and in a fixed vertical plane offset to the right of the vertical axis of the cutter bar when the tool is viewed as in Figure 2.

Extending downwardly from the depressed end of the spiral anvil 31^a is a vertically extending solid post 41 of generally cylindrical shape, the inner side of this post being milled out, as at 42, to provide a vertically elongated seat for the stationary cutting blade 32 already referred to above. The latter blade is similar in construction to that of the upper blade 23 in that it is provided with a beveled shearing edge 43 and with an elongated recess 44 in the body thereof, the base wall of the recess being longitudinally slotted, as at 45. The blade 32 is secured firmly in its seat 42 by means of a bolt 46 the threaded shank of which projects laterally through the post 41 and the slot 45 of the blade for engagement by a nut 47 seated in the recess 44. It will be apparent that the blade 32 may be adjusted vertically within its seat to the extent permitted by the length of the slot 45. In order to further secure the blade in its adjusted position against vertical displacement under the impact of each shearing stroke, the bottom end of the blade is preferably backed up by an axially adjustable screw 48 which in turn is locked in place by a laterally extending set screw 49.

It will be noted that when the cutting blades 23 and 32 are respectively mounted in position and adjusted properly in their seats, the shearing edges thereof are so angularly related as to permit free and easy feeding of the sheet material to be cut between and through said edges of the blades. Of course, in practice the tool is generally fed into and through the material along prescribed lines of cut, during which operation the sheared edges of the material are respectively deflected above and below the anvil 31^a so that one portion of the sheared material rests upon the upper surface of the anvil, while the other portion rides beneath the anvil in close contact with its under surface.

In order to provide the operator of the tool with the fullest possible view of the line of shearing, the flanges 38-39 of the vertically aligned sleeve 18 and post 37 are commonly cut away as at 50-50, along a transverse line substantially coincident with the plane of vertical reciprocation of the upper cutter blade 23. In operating the tool for shearing material along a prescribed line of cut, the tool may be fed straight through the material for making a straight line cut of indefinite length, or it may be turned to the right or to the left to shear the material along irregular or curved lines. When cutting the material along a line curving to the right of the shearing axis, such line of cut may curve from a straight line of infinite radius to a curved line of a radius as small as that of the upper post 37 of the anvil unit. On the other hand,

when the material is cut along a line curving to the left of the shearing axis, the smallness of the radius of such curvature is limited only by the radius of the lower depending post 41 of the anvil unit. Inasmuch as both of the oppositely projecting posts 37 and 41 are of small external diameter, the material may be sheared in either direction along lines of exceedingly small radii of curvature and with maximum visibility to the operator of the line of cut.

Due to the fact that the lowering depending post 41 with its associated cutting blade 32 is of relatively small overall diameter, it becomes possible to insert said post through a small opening formed in the sheet material preliminarily to effecting an inside cut in such material. This is an important feature of the present tool, because motor-driven shears prior to the invention have not been constructed to facilitate making inside cuts except in cases where the sheet material is initially provided with an excessively large opening into which the head of the tool may be inserted.

It will be understood, of course, that the present invention is susceptible of various changes and modifications which may be made from time to time without departing from the general principles and real spirit of the invention, and accordingly it is intended to claim the same broadly, as well as specifically, as indicated by the appended claims.

What is claimed as new and useful is:

1. In a hand-held motor-operated shearing tool, a shearing head comprising a pair of relatively movable cutting blades respectively having overlapping shearing edges forming an acute angle therebetween, a vertically reciprocable bar constituting a mounting for one of said blades, a tubular guide sleeve for the upper portion of said reciprocable bar, a tubular extension of said sleeve detachably secured to the latter in embracing relation with respect to the lower portion of said reciprocable bar, said tubular extension being of an overall external diameter substantially equal to that of said guide sleeve, a spiral anvil integral with and springing downwardly and laterally from the lower end of said extension toward a region spaced to one side of and below said lower end of said extension, the marginal edge of the upper part of said anvil being tangential with the external surface of said tubular extension, and a solid post depending from the depressed end of said spiral anvil, said solid post being disposed laterally to one side of and below said tubular extension with the vertical axis of said post and extension in parallel relation, said solid post constituting a mounting for the other one of said cutting blades.

2. In a hand-held motor-operated shearing tool, a shearing head comprising a vertically reciprocable cutter bar having a cutting blade op-

eratively mounted upon one face thereof, a tubular guide sleeve embracing the upper portion of said cutter bar and a combination work-supporting anvil and stationary cutter blade carrier detachably carried by said guide sleeve, said combination anvil and blade carrier including a part constituting a tubular extension of said guide sleeve and a laterally extending part in the form of a spiral platen tapering in cross-section from 10 a relatively thick outer edge toward a thin inner edge, and having an upper surface which inclines from one side of the axis of reciprocation of said cutter bar downwardly, the marginal edge of said upper surface of the platen being tangential to said tubular extension of the combination anvil and blade carrier, the depressed end of said spiral platen being provided with a stationary cutting blade carrier in the form of an integral depending post of relatively small transverse cross-section disposed in laterally offset relation with respect to said reciprocable cutter bar and with its vertical axis paralleling that of said bar.

3. In a shearing tool as defined in claim 2 25 wherein said last-mentioned depending post is recessed in one vertical face thereof to provide a seat for said stationary cutting blade, and wherein a cutting blade is adjustably positioned in said seat.

4. In a shearing tool as defined in claim 2 30 wherein the adjoining ends of said guide sleeve and tubular extension are respectively provided with mating flanges adapted to be bolted together, said flanges being commonly cut away immediately above the shearing zone to provide maximum view of said zone to the operator of the tool.

5. In a shearing tool as defined in claim 2 35 40 wherein the tubular extension forming part of said combination anvil and blade carrier is notched in one side thereof to provide a vertically extending guideway for the cutting blade mounted upon said reciprocable cutter bar.
